LADDER EXTENSION

Jesse De Forest Chase, Kansas City, Mo.

Application November 10, 1944, Serial No. 562,815

2 Claims. (Cl. 228—63)

1

The present invention relates to new and useful improvements in attachment for ladders and more particularly to an extension adapted to be attached to the lower end of one of the side rails of the ladder to increase the length thereof whereby to permit the ladder to stand level on uneven surfaces.

An important object of the present invention is to provide a ladder extension of this character which may be easily and quickly attached in position to either rail of the ladder and which at the same time is strong and durable, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a fragmentary front elevational view of a ladder showing the extension in position thereon.

Figure 2 is a transverse sectional view taken substantially on a line 2—2 of Figure 3, and

Figure 3 is a side elevational view of the extension and with parts broken away and shown in section.

Referring now to the drawing in detail wherein for the purpose of illustration I have disclosed a preferred embodiment of the invention, the numeral 5 designates the pair of side rails of the ladder and with the ladder rungs indicated at 6.

The extension comprises a short piece of material 7 of a cross-sectional area substantially equal to that of one of the rails 5 and preferably made of wood and adapted for placing in facing contact with the outer surface of one of the rails as shown to advantage in Figure 1 of the drawing.

To one edge of the member 7 is attached a pair of U-shaped plates 8 adapted to receive both the rail 5 and the member 7 within the legs 9 of the plate, the plate being free of the rail 5 and formed at its inner surface with serrations or teeth 10 adapted to bite into the edge of the rail.

The opposite edge of the member 7 is formed with vertically spaced recesses 11 within which coil springs 12 are positioned and through which pins 13 extend with their inner ends embedded in the member 7 and their outer ends formed with heads 14 spaced outwardly from the adjacent edge of the extension member 7.

A clamping plate 15 extends longitudinally along the edge of the member 7 and covers the

recesses 11, the plate being slidably mounted on the pins 13 and retained in position thereon by the heads 14 of the pins.

The plate 15 is formed with a pair of lateral extensions 16 extending transversely of the adjacent edge of the rail 5 and formed at their ends with angular flanges 17 adapted to engage the side edge of the rail 5. The inner surface of the extensions 16 are also formed with serrations or teeth 18 adapted to bite into the edge of the rail.

A U-shaped plate 19 has its leg portion recessed in the opposite side of the member 7 flush with the surfaces thereof with the ends of the plate 19 projecting outwardly beyond the plate 15 and provided with a pin 20 on which a lever 21 is pivotally mounted, the lever having a cam head 22 at its pivoted end adapted to bear against the plate 15 to force the same inwardly against the member 7 and with the extension 16 in clamping engagement with the rail 5 as shown in Figure 3 of the drawing.

The lower end of the member 7 is formed with a plurality of transversely extending openings 23 adapted to receive a pin 24 for underlying the rail 5 to further support the lower end of the rail 5 on the extension 7. The openings 23 are preferably arranged in vertical rows as shown in Figure 3 of the drawing with the openings of one row staggered with respect to the openings of the other row, the pin 24 being selectively positioned in the openings of either row in order that a relatively fine adjustment of the member 7 relative to the rail 5 may be obtained.

In the operation of the device when the lever 21 is moved into its lowermost position, the clamping plate 15 and extensions 16 will be projected outwardly from the member 7 by the spring 12 whereby the extension member 7 may be adjusted longitudinally of the rail 5 and the pin 24 is then inserted into one of the openings 23 to retain the ladder in its adjusted position. The lever 21 is then raised upwardly so as to cause the cam 22 to engage the plate 15 and force the same inwardly against the member 7 thereby forcing the extensions 16 inwardly against the rail 5, the plates 8 and the extensions 16 thus cooperating to clamp the extension member 7 to the opposite edges of the rail 5.

It is believed that the details of construction, operation and advantages of the device will be readily understood from the foregoing without further detailed explanation.

Having thus described the invention, what I claim is:

1. A ladder extension comprising an elongated

member adapted for placing against one side of a ladder rail, a pair of stationary U-shaped clamping plates secured in vertically spaced relation to said member and adapted to receive an edge of both the ladder rail and said member for relative sliding movement and to secure the member against lateral movement from the rail as well as against forward or rearward tilting movement on the rail, a movable clamping plate carried by the member, cam means engaging said movable plate and adapted for moving the movable clamping plate into clamping engagement with an opposite edge of the ladder rail, and spring means yieldably urging the movable clamping plate out of clamping engagement.

2. A ladder extension comprising an elongated member adapted for placing against one side of

a ladder rail, a pair of stationary U-shaped clamping plates secured in vertically spaced relation to said member and adapted to receive an edge of both the ladder rail and said member for relative sliding movement and to secure the member against lateral movement from the rail as well as against forward or rearward tilting movement on the rail, a pair of pins projecting from a relative opposite edge of the member, a movable clamping plate slidably mounted on the pins, cam means carried by the elongated member and adapted for moving the movable clamping plate into clamping engagement with an adjacent edge of the ladder rail, and spring means yieldably urging the movable clamping plate out of clamping engagement.

JESSE DE FOREST CHASE.
